UNITED STATES PATENT OFFICE.

JOSEPH W. FROST, OF NEW YORK, N. Y.

ELECTRIC FIRE-ARM.

SPECIFICATION forming part of Letters Patent No. 319,898, dated June 9, 1885.

Application filed September 19, 1884. (No model.)

To all whom it may concern:

Be it known that I, JOSEPH W. FROST, of New York, in the county of New York and State of New York, have invented certain new and useful Improvements in Electric Fire-Arms; and I do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal sectional view of my improved electrical fire-arm. Fig. 2 is a similar view of a modification of the same, and Fig. 3 is a perspective view of the cartridge used in the same.

Similar letters of reference indicate corresponding parts in all the figures.

My invention has relation to fire-arms in which the charge is ignited by electric spark or heat; and it consists in the improved construction and combination of parts of a fire-arm in which the charge, which is contained in a cartridge having a penetrable head, is ignited by means of either a spark generated between two points penetrating the head of the cartridge by closing an electric circuit or by the heat generated in a thin wire penetrating the head of the cartridge by closing the circuit, as hereinafter more fully described and claimed.

In the accompanying drawings, the letter A indicates the stock of the gun or other arm, which stock is hollow and contains the battery B and an induction-coil, C, secured in any suitable manner; and D indicates the barrel, which is hinged to the stock in any suitable manner used in connecting the barrel to the stock in a breech-loading fire-arm. The frame E has a longitudinal perforation, F, in which slides a correspondingly-shaped block, G, which has two longitudinal perforations, H, through which the ends I of the wires J of the secondary circuit pass, the said wires being provided at their outer ends with points K, of platinum or other suitable metal, which points are removably secured upon the ends of the wires and project beyond the outer end of the sliding block. Inside the block the wires are formed into coils L, and are secured inside the coils in brackets M, projecting from

the inside of the frame or stock, the said coils serving to allow the wires to be stretched when the sliding block is pushed outward. 55 One end of a lever, N, is pivoted to the inner end of the sliding block, while the lever is pivoted upon a bracket upon the inner side of the frame, and the other end of this lever is pivoted to a sliding bolt, O, which slides in 60 a perforation, P, in the frame under the perforation F, and which bolt bears with its outer end against a downwardly-projecting lug, Q, upon the inner end of the barrel. A spring, R, serves to force this bolt outward, bearing 65 against the inner end of the bolt.

S is the trigger, which has a notch, T, in the rear edge of its plate U, which notch may be engaged by a sliding bolt, V, provided with a suitable handle or finger-piece, W, and sliding to the rear of the trigger, by means of which the trigger may be prevented from being pulled. The upper eccentric edge of the trigger-plate is covered with an insulating-strip, X, and bears against a spring, Y, which 75 is suitably connected with the end of one of the wires Z of the primary or battery circuit and secured at one end, and the other of these wires is connected to a strip or bar, A', which is secured slightly above and forward of the 80 spring, having its free end pointing toward the free end of the spring and secured upon a screw, B', which screw serves to raise or lower the free end of the strip farther from or nearer to the free end of the spring, so that the free 85 end of the spring must be raised more or less by the eccentric edge of the trigger-plate, and consequently the trigger pulled harder or less hard, according to the ease with which it is desired to have the gun fired, the spring coming in contact with the strip closing the circuit and causing a spark to pass from the points in the sliding block.

The cartridge, which will be made the subject of a separate application, is shown at C', 95 and has a metallic head, D', provided with a central aperture, E', covered with a penetrable covering, F', or, if desired, with an explosive covering.

It will be seen that after the cartridge has 100 been inserted into the breech of the barrel, and the barrel is tilted downward in its position for firing, the downwardly-projecting lug upon the rear end of the barrel will press against

the sliding bolt in the frame, which will be forced inward, which will tilt the lever inside the frame, which again will force the sliding block outward, causing the igniting points to 5 penetrate the penetrable covering of the cartridge. When, now, the trigger is drawn, the circuit will be closed and a spark will pass between the ends of the points, igniting the charge of the cartridge. It follows that the 10 sliding bolt and lever may be dispensed with, when the sliding block may be operated in any other suitable manner; or the block may be stationary and the points made to enter the cartridge by simply closing the breech 15 against the frame.

In Fig. 2 a slight modification of the gun is shown, in which the induction-coil may be dispensed with, and in which the points in the block are either brought into immediate 20 contact or connected by means of a thin wire, and it will be seen that when the circuit is closed the points or the thin wire will become incandescent or red hot, and in this manner 25 ignite the charge or the explosive covering of the cartridge.

I am aware that fire-arms have been made in which a point, which forms the electrode for one end of the electric current, is forced into a cartridge having a metallic body within 30 it, which body is in contact through the sides of the cartridge with the bore of the barrel, to which the other end of the current is conveyed, so that the electric spark will be formed between the point and the metallic body 35 within the cartridge; but this construction involves the difficulty, that for one thing the cartridge is rather complicated and difficult to manufacture, and next that by firing the arm the bore of the barrel will be apt to be 40 come coated with soot, &c., which may prevent contact between the metallic body in the cartridge and the barrel, and thus prevent the firing.

I am likewise aware that a fire-arm has 45 been made in which the point at one end of the current projects into a loose charge of powder, and that in firing the arm the other end of the current is brought into contact with the barrel, which thus causes a spark to 50 pass between the point and the barrel through the loose powder; but this arm is likewise apt to be rendered inactive by soot, &c., from the fired powder, as well as from defective insulation or other causes, while in my hereinbefore-described fire-arm the spark is formed 55 between the penetrating points, making the cartridge of nearly the same construction as the cartridge used in other breech loading-arms, and equally as simple in construction, 60 as well as insuring the certainty of a spark each time the current is closed. I therefore, being aware of the presence of the above mentioned constructions, do not claim, broadly, a fire-arm having a penetrating electrode; but 65 I claim—

1. In an electric fire-arm for firing a cartridge having a penetrable covering, the combination of the arm having a tilting barrel, two electrodes at the ends of the wires of an electric circuit secured reciprocatingly in the 7 breech-piece of the arm, means for projecting the same into the breech end of the barrel, and suitable means for closing the circuit, as and for the purpose shown and set forth.

2. The combination, in an electric fire-arm, 7 of the barrel having the downwardly-projecting lug, the frame having a larger and a smaller longitudinal perforation in its breech-block, the block sliding in the larger perforation in the breech-block and having the igniting- 8 points, the bolt sliding in the smaller perforation in the breech-block and having means for forcing it outward, and the lever pivoted upon the inner side of the frame between the perforations and pivoted at its ends to the 8 sliding block and bolt, as for the purpose shown and set forth.

3. The combination of the battery, the induction-coil, the wires of the primary circuit, the trigger having its upper edge covered with 9 insulating material, the spring attached to one of the primary wires and secured above the trigger, the strip secured forward of and above the spring and connected to the other primary wire, and the secondary wires provided at 9 their outer ends with the penetrating igniting-points projecting outside of the frame, as and for the purpose shown and set forth.

4. The combination of the trigger having the upper eccentric edge of its plate covered 10 with insulating material, the spring secured at one end above the said edge of the trigger, and the strip secured forward of and above the spring having its free end pointing towards the free end of the spring and secured at its 10 other end upon a screw, upon which it may be adjusted with its free end nearer to or farther from the free end of the spring, as and for the purpose shown and set forth.

5. The combination of the sliding block 11 having means for sliding it in and out, the wires of the secondary circuit secured inside the frame to brackets, formed into coils outside of the brackets, and passing through the sliding-block provided with the igniting- 11 points, the primary wires, the trigger, the spring connected to one of the primary wires and secured at one end above the trigger, and the strip connected to the other primary wire and secured adjustably forward of and above 12 the spring, as and for the purpose shown and set forth.

In testimony that I claim the foregoing as my own I have hereunto affixed my signature in presence of two witnesses.

JOSEPH W. FROST.
